United States Patent Office.

A. S. McCLURE, OF DUNCANNON, PENNSYLVANIA.

Letters Patent No. 63,069, dated March 19, 1867.

IMPROVED RAILWAY JOINT.

The Schedule referred to in these Letters Patent and making part of the same.

TO ALL WHOM IT MAY CONCERN:

Be it known that I, A. S. McCLURE, of Duncannon, Perry county, State of Pennsylvania, have invented new and useful improvements in Railway Tracks; and I do hereby declare the following to be an exact description thereof, reference being had to the accompanying drawings, and to the letters of reference marked thereon, making a part of this specification, in which—

Figure 1 represents a side view of the track with the ward rail set into the main rails.

Figure 2 is a top view.

Figure 3 is an opposite side view; and

Figure 4 an end view.

The nature of my invention consists in the construction of the ward rail, and the mode of fitting the ward rail into the main rails, and fastening the same by an opposite brace or guard rail with bolts.

A A represent the main rails, similar to the ordinary T-rails, with the outside top flanges cut out for the ward rail B to fit in. On the opposite side of the main rails a flat bar or guard-plate, C, rests against the main rails on each side of the joint D, and between the top and bottom of the flanges and base of the main rails, bevelled below so as to fit closely to rails, and under the top flanges of the main rails, to support and strengthen the flanges. The ward rail B is made of steel or rolled iron, and its top flange fits into the main rails and projects slightly beyond their outside flanges, and the car wheel passing over the joints is always on a solid, smooth surface. The main rail carries over the joint at the end of the ward rail B, and the ward rail carries over the joint D of the main rails A, so that if the joints were much open the wheel cannot drop in to create a concussion, and the continual jarring of the cars and noise are avoided; also much labor and expense are avoided to keep the ends of the main rails up that are the cause of constant repairs. The ward rail B and guard-plate C are fastened by bolts, extending through them and the main rails, the bolt-holes of the main rails being enlarged to allow for the expansion and contraction of the rails. The main rails rest on cross-ties G G G, with an iron plate, H, underneath the rails that supports the joint D, dispensing with the use of chairs.

What I claim as my invention, and desire to secure by Letters Patent, is—

The construction of the ward rail B, when fitted into the flanges of the main rails A, and fastened and supported by the guard-plate C, as herein described and for the purposes set forth.

A. S. McCLURE.
